WINDING CARRIER FOR FRESHLY SPUN
THREADS OF ARTIFICIAL SILK

Theodor Grauer, Horn, Switzerland, assignor to
the firm Feldmühle A. G. vormals Loeb
Schoenfeld & Co. Rorschach, Rorschach,
Switzerland

Application February 12, 1934, Serial No. 710,934
In Germany February 18, 1933

3 Claims. (Cl. 242—118)

This invention relates to winding carriers for
freshly spun threads of artificial silk.

It is a known fact that the thread coil formed
on a winding carrier by means of freshly spun
artificial silk shrinks during the drying follow-
ing the wet aftertreatment. In consequence
thereof, the material of the inner layers of the
thread coil which are prevented from contracting
on the winding carrier to the same degree as the
10 exterior layers presents different qualities as a
textile from those of the outer layers.

In an endeavour to eliminate this drawback
hitherto, quite a number of special constructions
of winding carriers have been proposed which
15 permit of subsequently reducing the length of
the circumference on which the thread is wound
particularly by moving inwardly the backs of
certain individual supporting members of the
winding carrier. Instead of using such specially
20 constructed winding carriers, it has already been
practised to remove the thread coils from the
winding carriers for the aftertreatments. How-
ever, the sealing of these adjustable winding car-
riers in a manner appropriate for the subsequent
25 aftertreatment of the thread coils by means of
the various liquids to be used, so that these li-
quids penetrate through the thread coil properly
without being caused to pass by the material in-
effectively by pressure or suction action, meets
30 with extraordinary difficulties.

In the winding carrier for freshly spun artifi-
cial silk, according to this invention, the entire
length between lateral circumferential marginal
35 portions and interconnecting supporting
members serves for receiving the thread mate-
rial which members due to being adjustable
permit of relaxing the thread coil formed which
closes the joints between the coil and the lateral
40 circumferential marginal portions in a manner
appropriate for the wet aftertreatment, whereby
the said members may be adapted for adjust-
ment in the axial or radial direction of the wind-
ing carrier.

Thus, with the winding carrier according to
45 this invention sealed joints are automatically
provided for on the termination of the winding
operation, while the thread coil is still adapted
to be relaxed in such a manner that any liquids
serving for the aftertreatment of the thread coil
50 are compelled to penetrate through the thread
coil exclusively. At the same time the lateral
circumferential marginal portions of the wind-
ing carrier afford protection for the thread coil
against exterior influences and increase the sta-
55 bility of the winding carrier.

In the accompanying drawings several con-
structional forms of the invention are illustrated
by way of example only, in which

Figs. 1 and 2 illustrate a constructional form
of the invention in a fragmentary section and a
fragmentary side elevation respectively. 5

Figs. 3 and 4 show in a fragmentary trans-
verse section and a corresponding plan view re-
spectively a detail of this construction.

Figs. 5 and 6 show another constructional form
of the invention in an axial section and a front
elevation respectively, while 10

Figs. 7 and 8 represent views of details of this
construction.

In the constructional form of the winding car-
rier shown in Figs. 1 and 2 in a section and a side
elevation respectively, numerals 1 and 2 designate
annular end discs or plates which are rigidly
joined together in spaced relation by bolts 3. The
end plates are embossed at circumferentially
spaced positions with guide slots 4, 5, in which the
ends of thread supporting rods 6 are slidably ac-
commodated. The side walls of the embossments
prevent circumferential movement of the rods 6
while the end walls thereof limit the radial
movement of said rods within predetermined
limits and the bottom walls prevent axial displace-
ment thereof. The thread supporting rods are
thus restricted in movement in every direction.
Since the embossments are closed at the bottoms, 20
the guiding and restriction of the thread sup-
porting rods is provided for without openings
through the end discs which would permit leak-
age. The thread supporting rods 6 are normally
pressed outwardly in the guide embossments to-
ward their extreme outward limit by a resilient
30 annular spring 7 located midway between the end
discs within the thread supporting rods. This
spring is held in this midway position by several
pairs of studs 8 mounted on bolts 3 and engaging
35 opposite sides of the spring 7.

Figs. 3 and 4, show on a larger scale a side
elevation and a plan view respectively of a detail
of this construction, the ends of the springy an-
nulus 7 being provided with hinge portions 9 and
45 10 respectively, and a link 11 serves for connecting
the hinge portion 9 with a swingable control arm
12. In the position of the control arm 12 shown
in full lines, the springy annulus is adjusted to
maximum circumferential length, whereby the 50
supporting members 6 assume their outermost po-
sitions on the winding carrier. By slightly rock-
ing the control arm 12 from the respective posi-
tion in the direction of the arrow shown in Fig.
55 3, a partly collapsed condition of the winding car-

rier is obtained by the springy annulus 7 being correspondingly contracted. Advantageously, means are provided for retaining the swingable control arm 12 in the respective intermediate position. On subsequently swinging the control arm 12 into the position shown in chain dotted lines in Fig. 3, the springy annulus 7 is moved into its maximum contracted condition, for correspondingly relaxing the thread coil.

10 The thread coil is formed in the receiving groove 13 of the winding carrier between the side walls 1, 2 of this groove, which coil provides in conjunction with these side walls tightly sealed joints against the liquid of the after-treatment, as these 15 joints between the side walls and the thread coil are free from any slots. These lateral marginal portions of the winding carrier permit of turning the carrier by frictional engagement of their circumferential edges, without disturbing the artificial 20 thread material. After the texture of the silk is slightly loosened by the winding carrier being caused to assume its partly collapsed condition, the silk is penetrated by the respective liquid in a uniform and gentle manner. In the completely collapsed condition of the winding carrier, however, the silk is adapted to shrink unhindered while being dried (for example 6 to 10%) and need not be touched by the hand nor removed from the winding carrier. By this means, the obtainment 25 of an absolutely uniform product even in large size thread coils is ensured.

Experience has shown that it is particularly advantageous to effect the wet treatment on a rigid carrier and to dry the material on a readily yielding supporting base, so that the thread in shrinking during the drying is still opposed by a certain resistance acting from the innermost to the outermost layers of windings.

A winding carrier of this type is shown in Figs. 40 5 and 6 in an axial section and a front elevation respectively, whereas the Figs. 7 and 8 show details of this carrier.

The winding carrier as exemplified in these figures is in the form of a spool having a cylindrical barrel 15 which is provided at the ends with flanges 16 and 17 respectively which adjoin the barrel with a steeper portion and are gradually deflected outwardly to merge into a cylindrical shape. This form of the spool has proven to be 50 most advantageous.

Along the circumference of this spool longitudinal bars 18 are divided equal distances apart and provided at both of their ends with notches 19 (Fig. 7). These notches 19 accommodate springy rings 20 and 21 which are guided on their inner sides by the flanges 16 and 17 respectively and thus prevent the bars 18 from dropping off in the axial direction. The latter are inserted in slots 23 in the flanges 16 and 17 (Fig. 6) and 55 thus limited in their outward movements in the radial direction.

The springy rings 20 and 21 are adapted to act in the manner of a locking device. The rings are tensioned, that is positively forced outwardly, 60 when the two levers 25 and 26 of the locking mechanism are locked in the dead centre position. In the relative position of the parts of the locking device shown in Fig. 8 the springy ring is released and is thus adapted to resiliently resist 65 the pressure exerted on the longitudinal bars 18 by the thread coil. The lever 25 is provided with an extension 27 which serves as a handle for controlling the locking device.

If required, the barrel of the spool may be punctured.

The spool is mounted on the spool holder of the spinning machine with the springs 20 and 21 in tensioned condition. Thereupon the textile is applied thereto with the thread being cross wound in a suitable manner.

The silk coil as designated by 30 in Fig. 5 covers the longitudinal bars 18, the flanges 16 and 17 and the slots 23 situated inwardly on the latter completely. The coil can be wound to any desired thickness, as the spool, owing to its particular construction, is adapted to equalize any differences in tensioning between the inner and outer layers. When the spool is doffed from the spinning machine and placed in position in the washing and aftertreating tubs, it can be readily 15 subjected to a vacuum or to pressure as it is completely closed by the silk coil owing to its particular construction.

After the wet treatment, as washing, desulphurizing, bleaching, shading off to a desired hue and so forth, the spool is collapsed by releasing the locking mechanism as described in connection with Fig. 8 and carefully inserted in the drying oven. Alternatively, the spool is previously subjected to centrifugal action. Due to the fact 20 that the springy rings 20 and 21 exert at all times a gentle pressure on the thread coil from within, the layers of windings are retained in their initial 25 positions and thus kept from tangling.

The drying is effected under equal conditions 30 for the inner as well as the outer layers of windings of the thread. The innermost and the extreme outermost layers dry out first and thus begin to shrink prematurely. While the outer layers are resisted by the bulk of the layers of 35 the coil, the inner layers are resisted in a similar manner by the released bars 18.

The trend is to keep the resistance opposed by the resilient bars during the shrinking within the limits of the reaction exerted on the outermost 40 layers by the inner layers.

The artificial silk wound on the spool according to the invention and subjected to the after-treatment while still on the spool is of surprisingly uniform quality throughout the coil. The 45 unwinding of the silk from this spool can be carried out free from disturbances. Advantageously the silk is immediately twisted preferably on ring doubling machines rather than on balloon doubling machines.

I do not limit myself to the particular size, shape, number or arrangement of parts as shown and described, all of which may be varied without going beyond the scope of my invention as shown, described and claimed.

What I claim is:

1. In a winding carrier for freshly spun artificial silk thread, in combination, lateral marginal portions of the carrier disposed circumferentially thereof, supporting members for the thread material intercalated between said marginal portions in circumferentially spaced relationship and providing in conjunction with said portions a radially adjustable receiving groove to be substantially filled out with said material, radially directed guides provided on said marginal portions for said supporting members, a springy adjustable annulus cooperating with said supporting members for shifting the same radially outwardly along said guides, and control means for contracting said annulus for relaxing the wound-on material in said groove.

2. In a winding carrier for freshly spun artificial silk thread, in combination a rigid cylindrical barrel, radially outwardly flared marginal 75

end portions of said barrel having radially directed guide slots in circumferentially spaced relationship, supporting members for the thread material extending between said end portions and engaging with their ends into said guide slots for providing in conjunction with said end portions an adjustable receiving groove to be filled out with said thread material, adjustable springy annular abutments for said supporting members situated axially exteriorly of said receiving groove but interiorly of said marginal end portions for pressing said supporting members radially outwardly along said guide slots, and control means for said abutments for maintaining the same in their expanded relatively rigid condition of winding or in their relieved resilient condition respectively for relaxing the wound-on material in said groove.

3. A winding carrier for freshly spun artificial

silk threads having supporting members, lateral peripheral margins, the supporting members connecting the lateral peripheral margins forming therewith a peripheral channel for receiving the thread, said lateral peripheral margins having guides in which said supporting members lie and in which they are slidble, to reduce the diameter of the winding channel at any time for the relaxation of the thread winding, means for limiting the radial sliding of the supporting members in said guides, an open resilient ring for supporting the supporting members, and means including a pivoted control arm connected with the ends of said ring for expanding or contracting and holding said resilient member relatively unyieldingly to serve as a relatively rigid support for said supporting members.

THEODOR GRAUER.
